OTTO L. SCHASTEY, OF BROOKLYN, NEW YORK.

CLOTHESLINE SUPPORT.

1,414,217.

Specification of Letters Patent. Patented Apr. 25, 1922.

Application filed May 10, 1921. Serial No. 468,378.

To all whom it may concern:

Be it known that I, OTTO L. SCHASTEY, a citizen of the United States, and a resident of the city of New York, borough of Brooklyn, in the county of Kings and State of New York, have invented a new and Improved Clothesline Support, of which the following is a full, clear, and exact description.

10 This invention relates to improvements in clothes line supports, an object of the invention being to provide means for supporting an endless clothes line in such a manner that clothes may be hung upon a line within a 15 room and the endless line then operated to move the clothes through a window out of the room.

20 A great number of accidents have occurred in endeavoring to hang clothes on the ordinary endless line working upon pulleys since the housewife is forced to lean out of a window to place the clothes upon the line and is very liable to lose her balance and fall from the window.

25 An object of this invention, therefore, is to provide a clothes line supporting means, which will entirely obviate the danger of such accidents occurring, and which will be simple and practical in construction, strong 30 and durable in use, which will take up a small amount of space, which will be neat and attractive in appearance, and comparatively inexpensive to manufacture.

35 With these and other objects in view, the invention consists in certain novel features of construction and combinations and arrangements of parts as will be more fully hereinafter described and pointed out in the claim.

40 In the accompanying drawings:

Figure 1 is a view in side elevation illustrating my improved clothes line support in applied position, the dotted lines indicating the position of the support when clothes are 45 to be hung upon the line; and

Figure 2 is a broken edge view of the support.

Referring in detail to the drawings, 1 represents a window frame, the side members 2 of which, are formed with the usual channels or grooves 3, wherein sashes 4 are slidable. I have illustrated the lower sash as raised to its highest position and immediately below this sash adjacent the outer 55 edge of one of the side members 2 of the frame, a plate such as 5 is secured.

A spacing member 6 is fixed to the face of the plate 5 and a block 7 is pivotally connected to the spacing member by means of a pin or similar securing device designated by the reference numeral 8. A set screw 8' locks the pin against accidental withdrawal from the spacing member 6. The block 7 includes a sleeve 9, into which fits one end of a rod or pipe 10. Adjacent one side of the sleeve, an arm 11 integral with the block 7, carries a segmental channel guide bracket or block 12. At a point directly opposite on the other side of the pivot, a similar guide bracket 13 is carried by the member 7. A yoke 14 prevents a line 15 from slipping off of the block 13. The blocks 12 and 13 may be of the same size, if desired, or may be of different sizes, as illustrated in the drawings, their exact 75 shape of course, being immaterial to this invention.

Upon the free end of the rod 9, a collar 15' is mounted and is integral with a pair of laterally extending arms 16 and with a 80 U-shaped bracket 17 in alignment with the rod. A pulley 18 is mounted in the bracket 17 and the arms 16 carry guide sleeves such as 19.

An endless clothes line 15 is passed over 85 the block 13 through the yoke 14, through one of the sleeves 19 around the pulley 18 through the other sleeve 19 up over the block 12 and out around a pulley at some distance from the window, which does not 90 appear in the drawings.

A locking member such as 20 is pivotally supported on the plate 5 below the spacing member 6. The segment 12 is preferably integral with a pin 21 which extends 95 through the block 7 and has a wiping engagement with the swivelled locking member 20, as the arm 10 is swung toward the horizontal position illustrated in dotted lines in Figure 1. The locking member 20 100 is formed with an undercut curved recess 22, which accommodates the pin 21 when the arm 10 is in horizontal position.

The method of use of my improved support is as follows:

When it is desired to hang clothes upon the line 15, the arm 10 is swung to horizontal position, the pin 21 automatically locking with the member 20 and serving to retain said arm in the position illustrated in 110 dotted lines in Figure 1. The lower run of the clothes line 15 is slipped off the block

12. Clothes may be hung upon the line in the room and moved out through the window by pulling the line, as will be readily understood. After the clothes have been 5 hung up on the line, the locking member 20 is manually disengaged from the pin 21, the lower run of the clothes line is again lifted over the block 12 and the arm is moved to its normal depending position. In this position, the arm clears the sashes 4 so that the window may be closed. It will be noted that since the block 12 and the block 13 are on opposite sides of the pivot 8, a strain upon the line 15 caused by the weight of 15 the clothes or by the wind will not have a tendency to raise the arm 10 since the strain on one run of the line will be offset by the strain on the other run and the pull which will be exerted upon the arm 10 will be a 20 direct upward pull, which will of course have no effect upon the position of the arm.

Various slight changes and alterations might be made in the general form and ar-

angement of the parts described without departing from the invention and hence I do not wish to limit myself to the precise details set forth, but shall consider myself at liberty to make such slight changes and alterations as fairly fall within the spirit and scope of the appended claim.

I claim:

In a device of the character described, the combination with a support, of a block fixed to said support, an arm pivoted at one end 35 on the block and depending therefrom, a pulley at the free end of the arm, a pair of line supporting and guiding blocks at the pivoted end of the arm normally in vertical alignment with opposite sides of the 40 pulley, a locking member pivoted on the support, said locking member having a recess in its free end, and a pin integral with one of the line guiding blocks engageable with the locking member to swing and interlock with the same when the arm is swung to horizontal position.

OTTO L. SCHASTEY.
